CURTAIN FIXTURE

Filed Jan. 4, 1929

Inventor:
Edward E. Whitmore,
By *Crommelin, Frost & Ward*

UNITED STATES PATENT OFFICE

EDWARD E. WHITMORE, OF CHICAGO, ILLINOIS, ASSIGNOR TO THE ADLAKE COMPANY,
OF CHICAGO, ILLINOIS, A CORPORATION OF ILLINOIS

CURTAIN FIXTURE

Application filed January 4, 1929. Serial No. 330,170.

This invention has to do with curtain fixtures of the type wherein the curtain to which the fixture is attached constantly tends to wind up on a roller under the action of a torsion spring and the fixture is mounted in the lower end of the curtain and is provided with retractable members which engage frictionally within guides at the sides of the frame to prevent the curtain from being wound up.

The principal object of the invention is to provide an improved curtain fixture of the type described which will hold a curtain effectively in any desired position and will not rattle.

Another important object of the invention is to provide a curtain fixture of novel construction, arrangement and operation which is inexpensive to manufacture and will last indefinitely.

Other objects and advantages of the invention will be apparent to those skilled in the art upon a full understanding of the new fixture.

One form of the invention is presented herein for the purpose of exemplification, but it will of course be appreciated that the invention is susceptible of embodiment in other structurally modified forms coming equally within the scope of the appended claims.

In the accompanying drawing:

Fig. 1 is a top view of the fixture;

Fig. 2 is a side view of the same;

Fig. 3 is a sectional view through one end of the fixture, both ends being the same, showing the guide gripping member in released position; and

Fig. 4 is a corresponding view, showing the guide gripping member in operating position.

The fixture illustrated in the drawing includes a tube 10 which is adapted to be encased within the lower end of a spring-wound curtain. The tube carries two heads 11 and 12 which are adapted to ride up and down in two grooved guides 13 and 14 attached to the opposite sides of the associated window frame. The heads are provided with tubular portions 15 which slidably fit within

the ends of the tube, and with upper and lower rollers 16 which are adapted to bear without friction against the bottoms of the grooves in the guides. The heads are pressed outwardly with respect to the ends of the tubes by coil springs 17 which are compressed between washers 18 seated against the inner ends of the tubular portions of the heads and other washers 19 seated against the outer sides of constrictions 20 in the tube.

The tube also carries two rods 21 and 22. The inner ends of the rods are in screw-threaded engagement with two finger pieces 23 and 24 which project through axially elongated slots 25 and 26 in a plate 27 secured to the tube over an opening in the center of the same. The outer ends of the rods slidably fit within the tubular portions of the heads and bear against two rings 28 and 29 which are loosely confined within the heads. The rods are pressed outwardly with respect to the tube by means of coil springs 30 which are compressed between washers 31 seated against the inner sides of enlargements 32 on the rods and other washers 33 seated against the outer ends of alining member 34 in the tube at the center of the same.

The rods 21 and 22 are movable independently of the heads, and vice versa, but the extent of relative movement therebetween is limited by means of pins 35 which extend diametrically through the rods into axially elongated slots 36 in the tubular portions of the heads.

The rings 28 and 29 are to a certain extent free to shift about in the heads, but are limited in their movement by means of center pins 37 and upper and lower pins 38 and 39, all of which pins extend crosswise of the heads and are rigidly secured to the side walls thereof. The center pins pass through the openings in the rings, and serve, when the heads are removed from the guides, to limit the outward movement of the rings under the spring pressure applied thereto through the rods. The lower pins constitute stops for the rings when the same are pressed by the ends of the rods into frictional engagement with the bottoms of the grooves in

the guides and forced downwardly by the tendency of the curtain to move upwardly. The upper pins perform the same function as the lower pins if any downward force is applied to the lower end of the curtain without the finger pieces having first been pinched together to release the frictional engagement afforded by the fixture. The upper pins also render the heads reversible without affecting the gripping function of the rings in any way.

In order to raise or lower the curtain to which the fixture is applied, the finger pieces are pinched together. The heads remain at all times in spring-pressed frictionless engagement with the bottoms of the grooves in the guides, thereby preventing any possible rattling of the rollers in the heads. When the finger pieces are pinched together, the outer ends of the rods withdraw from engagement with the rings, and the latter move back into the heads out of binding engagement with the bottoms of the grooves in the guides. When the finger pieces are released, at any desired elevation of the lower end of the curtain, the rings are immediately forced by both the spring action on the rods and the spring action on the curtain into frictional engagement with the bottoms of the grooves in the guides against the lower pins in the heads, thereby effectively preventing the curtain from moving upwardly.

I claim:

1. In a curtain fixture, a tube adapted to be secured to the lower end of a spring-wound window curtain, outwardly spring-pressed heads at the ends of the tube adapted to engage with guides at the sides of the frame in which the curtain is mounted, outwardly spring-pressed rods extending through the tube into the heads, and members confined loosely within the heads at the ends of the rods for frictional engagement with the guides under the pressure exerted thereon by the rods.

2. In a curtain fixture, a tube adapted to be secured to the lower end of a spring-wound window curtain, outwardly spring-pressed heads at the ends of the tube adapted to engage with guides at the sides of the frame in which the curtain is mounted, outwardly spring-pressed rods extending through the tube into the heads, and rings confined loosely within the heads at the ends of the rods for frictional engagement with the guides under the pressure exerted thereon by the rods.

3. In a curtain fixture, a tube adapted to be secured to the lower end of a spring-wound window curtain, outwardly spring-pressed heads at the ends of the tube adapted to engage with guides at the sides of the frame in which the curtain is mounted, outwardly spring-pressed rods extending through the tube into the heads, rings positioned within the heads at the ends of the rods for friction-

al engagement with the guides under the pressure exerted thereon by the rods, and means in the heads beneath the rings for holding the latter in wedging positions against the guides when forced outwardly by the ends of the rods.

4. In a curtain fixture, a tube adapted to be secured to the lower end of a spring-wound window curtain, outwardly spring-pressed heads at the ends of the tube adapted to engage with guides at the sides of the frame in which the curtain is mounted, outwardly spring-pressed rods extending through the tube into the heads, rings positioned within the heads at the ends of the rods for frictional engagement with the guides under the pressure exerted thereon by the rods, and pins extending crosswise of the heads above, below, and through the rings for limiting the movement of the rings when the latter are forced outwardly by the ends of the rods.

5. In a curtain fixture, a tube adapted to be secured to the lower end of a spring-wound window curtain, outwardly spring-pressed heads at the ends of the tube adapted to engage with guides at the sides of the frame in which the curtain is mounted, outwardly spring-pressed rods extending through the tube into the heads, rings positioned within the heads at the ends of the rods for frictional engagement with the guides under the pressure exerted thereon by the rods, pins extending crosswise of the heads through the rings for limiting the outward movement of the rings, and other pins extending crosswise of the head below the rings for holding the rings in wedging positions when forced outwardly by the ends of the rods into engagement with the guides.

In witness whereof I have hereunto subscribed my name.

EDWARD E. WHITMORE.
